UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-SEWING MACHINE.

Application filed May 9, 1927. Serial No. 189,792.

This invention relates to buttonhole sewing machines of that type adapted to sew a buttonhole with an eye at one end and it has particular reference to means for forming the bar at the end of the button hole opposite to the eye. This bar is sometimes formed by a line of stitching extending lengthwise of the buttonhole and beyond the buttonhole slit.

In some sewing machines which have been heretofore employed for forming a buttonhole with this type of bar the cam by which the stitch-forming mechanism and work-holding means are positioned for forming the bar, and which may be referred to as a "barring cam," has been formed as an integral part of the main cam which controls the feeding of the work during the stitching and the lateral shifting of the work necessary to form the eye of the buttonhole, and has been without any adjustment for different lengths of buttonholes. Each machine, therefore, has been adapted to make a bar of this type on a buttonhole of one size only and if it is desired to make a bar of this type on a different size of buttonhole it has been necessary to build another machine especially adapted for such other size.

It has also been proposed to provide a sewing machine adapted to sew a buttonhole having the above-mentioned type of bar with a removable and interchangeable cam by which the length of the buttonhole is determined. With this type of sewing machine there will be one of these interchangeable cams for each length of buttonhole and whenever it is desired to change the length of buttonhole it is necessary to remove the cam from the machine and replace it by another cam of the proper construction to make a buttonhole of the length desired. One of the objects of my present invention is to provide an improvement in buttonhole sewing machines of the type adapted to sew a buttonhole with a bar at one end extending in the direction of the length of the buttonhole, by which buttonholes of different lengths may be sewed without the necessity of removing any part of the machine and replacing it by another part and simply by making an adjustment of the parts in the machine, the

same parts being used for buttonholes of different lengths by merely being adjusted as to their position.

In carrying out my invention I provide a barring cam which is separate from the main cam and which is associated with the adjustment by which the length of the buttonhole is determined so that whenever adjustment is made to give a longer or shorter buttonhole the barring cam is simultaneously adjusted to produce properly the desired bar on the longer or shorter buttonhole. 55 60

Another object of the invention is to provide an improved structure for forming a bar of the above type which is so constructed that the length of the bar may be changed or adjusted without adjusting the length of the buttonhole. 65

Another object of the invention is to provide a buttonhole sewing machine of this type which is constructed so that the barring mechanism can be rendered inoperative if it is desired to sew an unfinished buttonhole without the bar. 70

In order to give an understanding of the invention I have illustrated in the drawings a selected embodiment thereof which will now be described after which the novel features will be pointed out in the appended claims. 75

Fig. 1 is a side view of a sewing machine embodying my invention; 80

Fig. 6 is a view of the upper side of the main cam showing the feeding cam groove; 90

Fig. 7 is a fragmentary sectional view showing the controlling means by which the length of the buttonhole is determined;

Fig. 8 is a fragmentary sectional view showing the position of the pins 47, 48 during the sewing around the eye of the buttonhole; 95

Fig. 9 is a section on the line 9—9, Fig. 2;

Fig. 10 indicates a partially completed buttonhole;

Figs. 11 and 12 show buttonholes of different lengths formed with a bar;

Fig. 13 shows a buttonhole without the bar;

Fig. 14 shows a buttonhole with a short bar.

Figs. 10 to 12 show the well known type of buttonhole such as is made by the machine to which the present invention relates and in said figures 1 is the buttonhole slit having at one end the eye 2, and 3 and 4 indicate the side stitching along the sides of the buttonhole, this stitching being carried around the eye 2 as shown at 5, all as usual in buttonholes of this type. The end of the buttonhole opposite the eye 2 is provided with a bar 6 and this is formed by one or two lines of stitching 7, 8 which extend in the direction of the length of the buttonhole and are more or less superposed on each other, these lines of stitching being usually in the line of the buttonhole slit 1.

In sewing a buttonhole of this type the stitching usually begins at the point 9, (see Fig. 10) and during the first feeding movement the barring stitches 7 are formed. When the point 10 has been reached the work-holding means and stitch-forming mechanism are given a relative lateral movement so that as the feeding movement is continued the stitches 3 along one side of the buttonhole will be formed. When the eye end of the buttonhole has been reached the stitch-forming mechanism and work-holding means are given a back and forth lateral movement and at the same time the stitch-forming mechanism is turned about a vertical axis thereby forming the stitches 5 around the eye 2. The stitch-forming mechanism and work-holding means are then given a reverse feeding movement to form the stitches 4 along the opposite side of the buttonhole and when the point 10 has been reached the stitch-forming mechanism and work-holding means are given a relative lateral movement so that during the continued feeding movement the barring stitches 8 are formed which are more or less superposed on the barring stitches 7. This produces the bar 6 at the end of the buttonhole which extends in the direction of the length of the buttonhole.

As stated above some sewing machines of the above-mentioned type are constructed so that each machine can only sew a buttonhole of a single size while other machines have been constructed to provide for changing the length of the buttonhole by removing some part of the machine and substituting another part of a different shape. My present invention aims to provide means whereby buttonholes of different sizes and having the above-mentioned type of bar may be sewed on the same machine without removing any parts and simply by making proper adjustment of the parts already on the machine.

My present invention provides means whereby buttonholes of different sizes having this type of bar may be sewed on the same machine by making proper adjustments.

The work-holding means and the stitch-forming mechanism of the sewing machine herein illustrated are such as are commonly found in buttonhole sewing machines of this type. The work-holding means comprises the usual work clamps 11 which are pivotally mounted and adapted to clamp the work against clamp plates 12 that are supported on the bed 13 of the sewing machine. The stitch-forming mechanism comprises the usual needle 14 operating from above the work and the usual under thread handling mechanism situated beneath the bed plate and which is mounted on a turret 15 and which co-operates with the needle to concatenate the edge stitches around the buttonhole.

The stitch-forming mechanism is mounted on and carried by a head or frame 16 and is actuated from the drive shaft 17 journaled in said head all as usual in sewing machines of this type. For convenience I will refer to the frame 16 on which the stitch-forming mechanism is mounted as the stitch-frame and will refer to the bed 13 on which the work-holding means is mounted as the work-frame.

The relative movement between the stitch-forming mechanism and work-holding means is secured by moving the stitch frame 16 on the bed or work-frame of the machine all as shown in United States Patents No. 488,028, December 13th, 1892, and No. 494,280, March 28th, 1893. The stitch frame 16 carrying the stitch-forming mechanism has rigid therewith a cam casing 18 in which is rotatably mounted the main cam 19 by which the operations of the machine are controlled, one of the functions of this cam being to give back and forth feeding movement to the stitch frame 16. For this purpose the main cam has a feed groove 20 therein in which operates a roll carried by the lower end of a pin 21 that is fast to the bed frame or work-frame 13, the construction being such that as the cam 19 rotates said cam and consequently the stitch frame 16 is given a bodily back and forth movement all as more fully set forth in the above-mentioned patents.

In the operation of buttonhole machines of this type the machine is brought to rest at the end of a cycle of operations with the parts in buttonhole cutting position and when the machine is set in operation the cam 19 is given its initial movement by a high speed driving mechanism during which movement the stitch frame 16 is shifted from buttonhole cutting to stitching position. When stitching position has been reached the high speed driving mechanism is disconnected from the cam 19 and the clutch controlling the driving shaft 17 is engaged thereby setting said shaft in op-

eration and starting the stitch-forming mechanism. At this time the cam 19 is rotated at a slower rate of speed from the shaft 17, said cam giving the stitch frame 16 the necessary movements to cause the stitching to be formed around the buttonhole.

During the sewing around the eye of the buttonhole the stitch-forming mechanism is turned about a vertical axis by mechanism 10 similar to that shown in Patent No. 655,637, dated August 7th, 1900. This comprises a lever 56 pivoted to the gear casing 18 at 110 and connected by a link 111 to an arm 112 fast on a rock shaft 113. This rock shaft has fast 15 on it two gear sectors 114, 115 which mesh with gears 116 on the turret 15 and 117 on the carrier for the upper needle 14. This lever 56 has a follower 119 operating in a cam groove 118 in the under side of the cam 19 all 20 as illustrated in said patent, said cam causing the stitch-forming mechanism to make a rotation at each end of the buttonhole.

During the stitching around the eye of the buttonhole the head or stitch frame 16 is 25 given a back and forth lateral movement to form the eye by means similar to that shown in the various patents above referred to, such means comprising a sinuous cam groove 54 of special shape formed in the main cam 19 in 30 which operates a follower on the end of a lever 55 which is fast on a shaft 120 journalled in the portion 121 of the head, said shaft having on its upper end an arm 122 carrying a block 123 that is operating in a groove in the bed 35 frame, all as shown in said Patent No. 488,028.

The driving shaft 17 is driven from a driving pulley 22 and the clutch by which the shaft 17 is connected to the pulley 22 and the means for actuating said clutch are or may be 40 all as shown in United States Patent No. 713,764, November 18th, 1902, and, therefore, need not be described in great detail herein. It is sufficient to say that the clutch comprises a clutch dog 127 by which the pulley is connected to the shaft 17 and which dog is provided with a tail 23 and that the clutch is controlled by a clutch-controlling member 24 fast on a rock shaft 25, said member having a clutch-releasing portion 26 by which 45 the clutch is disengaged. When the stitch-forming mechanism is in operation the member 24 is held in its inoperative position shown in Fig. 7 by means of a latch 27 engaging a lug 28 on an arm 29 fast on the rock shaft 25. 50 and when the member 24 is in this position the clutch-releasing member 26 is out of the path of movement of the tail 23 of the dog and the clutch will thus operate to clutch the shaft 17 to the driving pulley 22. If the latch 55 27 is released from the lug 28 the spring 29 will swing the controlling member 24 forwardly to bring the clutch-releasing member 26 in the path of movement of the tail 23 of the clutch dog thereby disengaging the clutch 60 and bringing the shaft 17 to rest, all as de-

scribed in the above-mentioned Patent No. 713,764.

This disengaging of the clutch is accomplished automatically when the buttonhole has been completed by means of a latch-releasing bar 30 which is adjustably carried on the bed or work-frame 13 and which is so situated that during the forward movement of the frame 16 and when the stitching operation has been completed the lower end of 70 the latch 27 which is mounted on the frame, will engage the end of the latch-releasing bar 30 so that the continued forward movement of the frame 16 will disengage the latch thus allowing the clutch-releasing member 26 to be moved into position to engage the tail 23 and thus disengage the clutch, all as shown and described in the above-mentioned patent.

The machine herein shown is also provided with the usual means for determining the length of the buttonhole and by means of which the length of the buttonhole may be adjusted. The mechanism herein shown for this purpose is similar to that illustrated in above-mentioned Patent No. 713,764.

The rock shaft 25 has fast thereon an arm 31 to which is connected a link 32 having at its lower end a roll 33. The link is normally held in the position shown in Fig. 1 by means of a latch 34. The clutch-releasing bar 30 is provided with a low portion 35 which is situated beneath the roll 33 when the machine has come to rest at the end of a sewing cycle and said bar is also provided with the rise or cam 36 that is adapted to be engaged by the roll 33 when the stitch-frame 16 moves to the right.

The parts are shown in Fig. 1 in buttonhole cutting position, which is the position they occupy at the end of the sewing cycle and when the machine is at rest, the latch 27 being at this time disengaged from the lug 28 and the clutch-releasing member 26 being in its operative position.

As stated above when the machine is started in operation the head or frame 16 first is moved to the right to carry the parts from buttonhole cutting position to stitching position and as the frame moves to the right the roll 33 will engage and ride up the cam 36 thereby turning the rock shaft 25 and withdrawing the clutch-releasing member 26 from engagement with the tail 23 of the clutch dog as shown in Fig. 7. This will start the stitch-forming mechanism in operation as described in the above-mentioned patents and at the same time it lowers the lug 28 so that the latch 27 will snap over it thus locking the parts in this position. The point in the movement of the head 16 at which the stitch-forming mechanism is set in operation depends upon the location of the cam 36 and the bar 30 is adjustably secured to the bed or work-frame 13 so that the position of the cam 36 may be varied. If the bar 30 is moved to

the right a shorter buttonhole will be produced while if it is moved to the left a longer buttonhole will be produced. This construction for adjusting the machine for different lengths of buttonhole is similar to that described in the above-mentioned Patent No. 713,764. In fact, all of the mechanism as above described is such as is commonly found in sewing machines of this type and is illustrated and described in detail in the various patents above referred to.

In prior machines of this type the barring cam by which the work-holding means and stitch-forming mechanism are given a relative lateral movement at the end of the buttonhole slit to form the barring stitches 7, 8 in the line of the buttonhole slit is carried by the main cam 19. In my present invention I dissociate said barring cam from the main cam 19 and mount it independently of said cam 19 and also provide for its adjustment so that it will function properly when making buttonholes of any length. I preferably mount the barring cam on the work frame 13 and associate it with the adjusting member 30 by which the length of the buttonhole is adjusted so that whenever an adjustment is made to change the length of the buttonhole the position of the barring cam will be simultaneously adjusted whereby said barring cam will always function properly regardless of the adjustment for the buttonhole length.

The barring cam herein shown is indicated at 37 and it is in the form of a plate which is secured to the under side of the bed 13 and is adjustably secured to the forward end 38 of the bar 30 by means of a screw 39 which extends through a slot 40 formed in the bed plate. When the screw 39 is tightened the forward end 38 of the bar 30 and the barring cam 37 are clamped firmly against the top and bottom respectively of the bed plate and are thereby firmly clamped in position, but when said screw is loosened then the barring cam and the bar 30 may be adjusted as a unit.

The barring cam is shown as having two cam grooves 41, 42, each of which has an offset or cam portion 43 therein as best seen in Fig. 4.

The portion 44 of the frame 16 in which the turret 15 is mounted is provided with a bracket arm 45 having a head portion 46 in which is slidably mounted two pins 47, 48 which are adapted to co-operate with the grooves 41, 42 in giving the lateral jogging motion to the head or frame 16 for forming the barring stitches as said head or frame moves back and forth. One of the pins, the pin 48, is operating in its cam groove 42 during the stitching on one side of the buttonhole, the other pin 47 being at this time withdrawn from engagement with the cam plate as shown in Figs. 1 and 9, and said other pin

47 is operating in its cam groove 41 during the sewing on the second side of the buttonhole, the pin 48 being at this time withdrawn. When the upper end of either pin is in its cam groove the engagement of the pin with the walls of the groove will prevent any lateral movement of the stitch-forming mechanism, and the position of the stitch-forming mechanism laterally will be controlled by said pin.

Assuming that the upper end of the pin 48 is in its groove 42, as shown in Fig. 9, and that the parts are in the position shown in Fig. 2, it will be understood that as the head 16 moves to the right the stitch-forming mechanism will be given a lateral movement when the pin passes through the cam portion 43 of the slot, this lateral motion being that which occurs at the point 10 of the buttonhole and being that which differentiates the barring stitches 8 from the side stitches 3.

These pins 47, 48 operate successively as stated above, one pin being operative during the stitching on one side of the buttonhole and the other pin being operative during the stitching on the other side of the buttonhole. Said pins, therefore, control the position of the stitch-forming mechanism in a lateral direction during the formation of the barring stitches and side stitches on the buttonhole.

The means for controlling the pins will be presently described.

As stated above the stitch-forming mechanism has a lateral movement during the stitching around the eye 5 of the buttonhole, which lateral movement is controlled by the sinuous cam groove 54 co-operating with the lever 55 and, therefore, I have provided herein means to render both pins 47, 48 inoperative at the time that the eye of the buttonhole is being sewed so that the control of the head or frame 16 as to its lateral motion will at this time be transferred from the pins to the cam groove 54.

Means are also provided to render one pin operative during the sewing on one side of the buttonhole and the other pin operative during the sewing on the other side of the buttonhole. During the sewing on the first side of the buttonhole or while the head 16 is moving to the right Fig. 1 the pin 48 is operating in its slot 42 as shown in Figs. 2 and 9, the pin 47 being withdrawn, and during the sewing on the second side of the buttonhole the pin 47 will be operating in the cam groove 41 and the pin 48 will be withdrawn.

The pins are controlled by arms or levers 79, 80 which are pivoted on a stud 81 carried by the bracket 45. The forward end of the arm 79 is received in a groove 73 formed in the lower projecting end of the pin 47 and the forward end of the arm 80 is received in a similar groove 52 formed in the lower end

of the pin 48. Each arm is acted on by a spring 83 which normally tends to move the pins upwardly into engagement with the grooves of the cam plate 37.

5 The arm 80 has rigid therewith an arm 63 which is connected by a link 62 to an extension 58 rigid with the lever 56 by which the stitch-forming mechanism is turned about its vertical axis. The arm or lever 79 is fast 10 on a sleeve 61 mounted on a stud 81 and said sleeve has rigid therewith an arm 60 which is connected by a link 59 to another projection or ear 57 also rigid with the lever 56 but situated on the opposite side thereof from 15 the projection or ear 58. With this arrangement the swinging movement of the lever 56 by which the stitch-forming mechanism is turned around the end of the buttonhole will operate to shift the position of the pins.

20 With the parts in the position shown in Figs. 1 and 2 the pin 47 is depressed into inoperative position and the pin 48 is elevated but as the lever 56 swings into dotted line position Fig. 2 to turn the stitch-forming 25 mechanism around the end of the buttonhole the lever or arm 80 will be depressed while the arm 79 will be elevated. Similarly at the opposite end of the buttonhole the turning movement of the lever 56 to bring the parts 30 into the position shown in Fig. 2 will depress the pin 47 and allow the pin 48 to be elevated.

When the side stitching 3 (see Fig. 10) is about completed, and before the follower on the lever 55 enters the cam groove 54 to effect 35 the stitching around the eye of the buttonhole, the pin 48 is withdrawn from its operative engagement with its groove 42. For accomplishing this the lever 80 is provided with an upstanding arm 64 and the bed 13 is provided with the depending arm or bunter 65, the latter being so situated that it will engage the upstanding arm 64 just before the eye of the buttonhole is reached. The engagement of the arm 64 with the bunter 65 depresses the 40 lever 80 and withdraws the pin 48 from its slot 42 as will be obvious, (see Fig. 8).

The connection between the link 62 and the arm 58 is such as to permit the arm 80 to be actuated by the bunter 65 as above described without changing the position of the arm 58. As shown said arm 58 has a boss 140 thereon through which the end of the link 62 slides, said link having a nut 141 screw threaded thereto and by which the link 55 may be actuated when the lever 56 is operated. The link 59 has a similar connection with the arm 57.

During the sewing around the eye of the buttonhole the lever 56 is moved into the 60 dotted line position Fig. 2, thus allowing the arm 79 to move upwardly and its spring 83 will bring the pin 47 against the cam plate 37. As soon as said pin comes in line with its groove 41 by the lateral shifting movement 65 of the stitch-forming mechanism said pin

will drop into the groove 41 and thereafter during the further movement of the head 16 the movement of the stitch-forming mechanism laterally will be governed by the cam groove 41.

It will be noted on reference to Fig. 5 that the groove in which the follower on the lever 55 operates is provided with widened portions 130 at each end of the sinuous portion 54. During the time that the pins 47, 48 are 70 operating in their cam grooves the follower on the lever 55 is operating in the wide portion 130 of the cam groove, this wide portion providing sufficient play of the follower on the lever 55 so that said lever will not 75 interfere in any way with the lateral jogging movement of the head due to the cam portions 43 of the cam grooves 41, 42.

Since the barring cam 37 is connected to the controlling member 30 by which the length of the buttonhole is controlled it will be observed that the position of said cam will be adjusted simultaneously with the adjustment of the bar 30. Hence the barring cam will be positioned to function properly for 80 every length of buttonhole and, therefore, with this invention it is possible to sew buttonholes of any desired length with the bar 6.

My invention also provides means by which the barring cam may be rendered ineffective 85 so that buttonholes without the bar may be sewed. I accomplish this by providing means for shifting the position of the barring cam relative to the starting cam 36 so that the stitch-forming mechanism will not be started 90 in operation until after the pins 47, 48 have passed the cam groove 43 of the barring cam. This is provided for as shown in Fig. 3. The portion of the member 30 carrying the starting cam 36 is adjustably secured to the portion 38 to which the barring cam is secured 95 by the clamping screw 39. The part 38 is shown as provided with a slot 131 in which is received a screw 132 carried by the forward end of the part 30. When this screw 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 they may be clamped in adjusted position by tightening the clamp 132.

The construction above described has the further advantage that it permits bars of different lengths to be formed regardless of the size of the buttonhole. I have described above how when the barring cam is moved to a sufficient extent relative to the starting cam 36, said barring cam will be rendered 10 inoperative because during the movement of the head 16 the pins 47, 48 will have been carried past the cam portion 43 of the barring cam before the starting cam engages the roll 33 to start the stitch-forming mechanism in 15 operation. If, however, the barring cam is adjusted relative to the starting cam 36 for a distance less than that necessary to render said barring cam inoperative the result will be that a bar will be formed which is shortened 20 from the full length bar by an amount determined by the adjustment of the barring cam.

In Fig. 14 I have shown a buttonhole having a short bar. The barring cam may be adjusted so that it will be rendered operative at 25 such a point in the cycle of movement that only three or four stitches will be formed before the point 10 of the buttonhole is reached and the head is given its lateral movement to 30 shift from barring stitches to side stitches or the barring cam may be adjusted into position where a relatively long bar will be formed as shown in Fig. 12.

The adjustment for the length of the bar is 35 quite independent from that for the length of stitches so that a bar of any desired length or no bar at all may be formed on a buttonhole of any desired length.

While I have illustrated herein a selected 40 embodiment of my invention I do not wish to be limited to the constructional features shown.

I claim:

1. In a sewing machine, the combination 45 with work-holding means, of stitch-forming mechanism, a stitch-frame supporting the stitch-forming mechanism, a work-frame supporting the work-holding means, means to give the work-holding means and stitch-forming mechanism a relative feeding movement 50 in the direction of the length of the buttonhole, and means carried by the work-frame to cause said stitch-forming mechanism and work-holding means to have a relative lateral movement after the first few stitches 55 have been formed and again just before the last stitches have been formed thereby to form a bar extending in the direction of the length of the buttonhole.

2. In a buttonhole sewing machine, the combination with work-holding means, of stitch-forming mechanism, a stitch-frame carrying the stitch-forming mechanism, a work-frame carrying the work-holding 65 means, means carried by the stitch-frame to

give said work-holding means and stitch-forming mechanism a relative feeding movement longitudinally of the buttonhole, means carried by the work-frame to cause said work-holding means and stitch-forming 70 mechanism to have a relative lateral movement after the first few stitches have been formed and again just before the last stitches have been formed thereby to form a bar extending in the direction of the length of 75 the buttonhole.

3. In a sewing machine, the combination with work-holding means, of stitch-forming mechanism, a main cam for moving said work-holding means and stitch-forming 80 mechanism relatively to each other to cause the stitches to be formed along the sides and around the eye end of the buttonhole, and a stationary barring cam separate from the main cam by which the work-holding means and stitch-forming mechanism are given a relative lateral movement during the relative movement derived from the main cam thereby to form a bar at the end of the buttonhole. 90

4. In a sewing machine, the combination with work-holding means, of stitch-forming mechanism, a rotary main cam for moving said work-holding means and stitch-forming 95 mechanism relatively to each other to cause the stitches to be formed along the sides and around the eye end of the buttonhole, and a stationary barring cam separate from the main cam by which the work-holding means and stitch-forming mechanism are given a relative lateral movement during the relative movement derived from the main cam thereby to form at the end of the buttonhole a bar 100 extending in the length of the buttonhole.

5. In a sewing machine, the combination 105 with work-holding means, of stitch-forming mechanism, a main cam for moving said work-holding means and stitch-forming mechanism relatively to each other to cause the stitches to be formed along the sides and 110 around the eye end of the buttonhole, means by which the length of the buttonhole may be varied, and a barring cam separate from the main cam and operative for different lengths of buttonhole by which the work-holding means and stitch-forming mechanism are given a relative lateral movement during the relative movement derived from the main cam thereby to form a bar at the end of the buttonhole. 115

6. In a sewing machine, the combination with work-holding means, of stitch-forming mechanism, a main cam for moving said work-holding means and stitch-forming 125 mechanism relatively to each other to cause the stitches to be formed along the sides and around the eye end of the buttonhole, means by which the length of the buttonhole can be varied, and a barring cam separate from the main cam and operative for different 130

lengths of buttonhole by which the work-holding means and stitch-forming mechanism are given a relative lateral movement during the relative movement derived from the main cam thereby to form at the end of the buttonhole a bar extending in the direction of the length of the buttonhole.

7. In a buttonhole sewing machine, the combination with work-holding means, of 10 stitch-forming mechanism, a main cam for moving said work-holding means and stitch-forming mechanism relative to each other to cause the stitches to be formed along the sides and around the eye end of the buttonhole, an adjustable controlling member by 15 which the length of the buttonhole is determined, and a barring cam adjustable with said member by which the work-holding means and stitch-forming mechanism are given a relative lateral movement thereby to 20 form a bar at the end of the buttonhole.

8. In a buttonhole sewing machine, the combination with work-holding means, of 25 stitch-forming mechanism, a main cam for moving said work-holding means and stitch-forming mechanism relative to each other to cause the stitches to be formed along the sides and around the eye end of the buttonhole, an adjustable controlling member by 30 which the length of the buttonhole is determined, and a barring cam adjustable with said member by which the work-holding means and stitch-forming mechanism are given a relative lateral movement thereby to 35 form at the end of the buttonhole a bar which extends in the direction of the length of the buttonhole.

9. In a buttonhole sewing machine, the combination with work-holding means, of 40 stitch-forming mechanism, means to give said work-holding means and stitch-forming mechanism a relative movement of fixed amplitude longitudinally of the buttonhole, adjustable means for controlling the operation of the 45 stitch-forming mechanism by which buttonholes of different lengths may be formed, and other means adjustable with said last-named means to produce a relative lateral movement between the stitch-forming mechanism and work-holding means to form at the end of 50 the buttonhole a bar extending in the direction of the length thereof.

10. In a buttonhole sewing machine, the combination with work-holding means, of 55 stitch-forming mechanism, means for giving said work-holding means and stitch-forming mechanism a relative movement of fixed amplitude longitudinally of the buttonhole, adjustable means for controlling the operation 60 of the stitch-forming mechanism by which buttonholes of different lengths may be formed, a barring cam adjustable into different positions according to the length of the buttonhole being sewed, and means operated thereby to produce a relative lateral move-

ment between the stitch-forming mechanism and work-holding means by which a bar is formed at the end of the buttonhole.

11. In a buttonhole sewing machine, the combination with work-holding means, of 70 stitch-forming mechanism, means for giving said work-holding means and stitch-forming mechanism a relative movement of fixed amplitude longitudinally of the buttonhole, adjustable means for controlling the operation 75 of the stitch-forming mechanism by which buttonholes of different lengths may be formed, a barring cam, and means operated thereby to produce a relative lateral movement between the stitch-forming mechanism 80 and work-holding means by which a bar is formed at the end of the buttonhole, said barring cam being connected to and adjustable with said adjustable means.

12. In a sewing machine, the combination 85 with work-holding means, of stitch-forming mechanism, a main cam for moving said work-holding means and stitch-forming mechanism relatively to each other to cause the stitches to be formed along the sides and 90 around the eye end of the buttonhole, a stationarily mounted barring cam separate from the main cam by which the work-holding means and stitch-forming mechanism are given a relative lateral movement during the 95 relative movement derived from the main cam thereby to form a bar at the end of the buttonhole, and means to render the barring cam either operative or inoperative.

13. In a sewing machine, the combination 100 with work-holding means, of stitch-forming mechanism, a main cam for moving said work-holding means and stitch-forming mechanism relatively to each other to cause the stitches to be formed along the sides and 105 around the eye end of the buttonhole, a non-rotary barring cam separate from the main cam by which the work-holding means and stitch-forming mechanism are given a relative lateral movement during the relative 110 movement derived from the main cam thereby to form at the end of the buttonhole a bar extending in the length of the buttonhole, and means to render the barring cam either 115 operative or inoperative.

14. In a sewing machine, the combination with work-holding means of stitch-forming mechanism, a main cam for moving said work-holding means and stitch-forming mechanism relatively to each other to cause 120 the stitches to be formed along the sides and around the eye end of the buttonhole, means by which the length of the buttonhole may be varied, a barring cam separate from the main cam and operative for different lengths 125 of buttonhole by which the work-holding means and stitch-forming mechanism are given a relative lateral movement during the relative movement derived from the main cam thereby to form a bar at the end of the 130

buttonhole, and means to render the barring cam either operative or inoperative.

15. In a buttonhole sewing machine, the combination with work-holding means, of 5 stitch-forming mechanism, a stitch-frame carrying the stitch-forming mechanism, a work-frame carrying the work-holding means, means on the stitch-frame for giving relative feeding movement to the stitch-forming mechanism and work-holding means 10 in the direction of the length of the buttonhole, means on the work-frame for shifting the stitch-forming mechanism and work-holding means relatively in a lateral direction just after the stitching begins and before it stops thereby to form a bar at the end of the buttonhole which extends in the direction of the length thereof.

16. In a buttonhole sewing machine, the 20 combination with work-holding means, of stitch-forming mechanism, a stitch-frame carrying the stitch-forming mechanism, a work-frame carrying the work-holding means, means on the stitch-frame for giving relative feeding movement to the stitch-forming mechanism and work-holding means in the direction of the length of the buttonhole, means on the work-frame for shifting the stitch-forming mechanism and work-holding 25 means relatively in a lateral direction just after the stitching begins and before it stops thereby to form a bar at the end of the buttonhole which extends in the direction of the length thereof, and means to vary the length 30 of the bar.

17. In a buttonhole sewing machine, the combination with stitch-forming mechanism, of work-holding means, a stitch-frame carrying the stitch-forming mechanism, a work-frame carrying the work-holding means, a main cam on the stitch-frame for relatively feeding the stitch-forming mechanism and work-holding means in the direction of the length of the buttonhole, a barring cam on the 45 work frame, for giving the stitch-forming mechanism and work-holding means a relative lateral movement at the end of the buttonhole slit thereby to form a bar.

18. In a buttonhole sewing machine, the 50 combination with stitch-forming mechanism, of work-holding means, a stitch-frame carrying the stitch-forming mechanism, a work-frame carrying the work-holding means, a main cam on the stitch-frame for giving said 55 stitch-forming mechanism and work-holding means a relative feeding movement longitudinally of the buttonhole, a barring cam on the work-frame by which the stitch-forming mechanism and work-holding means are given 60 a lateral movement just after the stitching begins and just before it ends, whereby the buttonhole is provided with a longitudinally-extending bar.

19. In a buttonhole sewing machine, the 65 combination with stitch-forming mechanism,

of work-holding means, a stitch-frame carrying the stitch-forming mechanism, a work-frame carrying the work-holding means, a main cam on the stitch-frame for giving said 70 stitch-forming mechanism and work-holding means a relative feeding movement longitudinally of the buttonhole, a barring cam on the work-frame by which the stitch-forming mechanism and work-holding means are given a lateral movement just after the stitching 75 begins and just before it ends, whereby the buttonhole is provided with a longitudinally-extending bar, said barring cam being adjustable thereby to vary the length of the buttonhole.

20. In a buttonhole sewing machine, the combination with stitch-forming mechanism and work-holding means, of a stitch-frame carrying the stitch-forming mechanism, a work-frame carrying the work-holding means, means to give the stitch-forming mechanism and work-holding means a relative feeding movement longitudinally of the buttonhole, means for varying the length of the buttonhole, means carried by the work-frame 80 for giving the stitch-forming mechanism and work-holding means a relative lateral movement just after the stitching begins and before it ends thereby to form a bar extending longitudinally of the buttonhole.

21. In a buttonhole sewing machine, the combination with stitch-forming mechanism and work-holding means, of a stitch-frame carrying the stitch-forming mechanism, a work-frame carrying the work-holding means, means to give the stitch-forming mechanism and work-holding means a relative feeding movement longitudinally of the buttonhole, means for varying the length of the buttonhole, means carried by the work-frame 90 for giving the stitch-forming mechanism and work-holding means a relative lateral movement just after the stitching begins and before it ends thereby to form a bar extending longitudinally of the buttonhole, and means 95 whereby the length of the bar may be varied.

22. In a buttonhole sewing machine, the combination with a stitch-frame, of a work-frame, stitch-forming mechanism carried by the stitch-frame, work-holding means carried by the work-frame, a rotary cam carried by the stitch-frame for giving the stitch-forming mechanism and work-holding means a relative feeding movement longitudinally of the buttonhole, a non-rotary cam carried by the work-frame for giving the stitch-forming mechanism and work-holding means a relative lateral movement during the relative feeding movement thereby to form a bar at the end of the buttonhole.

23. In a buttonhole sewing machine, the combination with a stitch-frame, of a work-frame, stitch-forming mechanism carried by the stitch-frame, work-holding means carried by the work-frame, a rotary cam carried by

the stitch-frame for giving the stitch-forming mechanism and work-holding means a relative feeding movement longitudinally of the buttonhole, a non-rotary cam carried by the work-frame for giving the stitch-forming mechanism and work-holding means a relative lateral movement during the relative

feeding movement thereby to form a bar at the end of the buttonhole, said barring cam being adjustable whereby the length of the bar may be varied.

In testimony whereof, I have signed my name to this specification.

JOHN KIEWICZ.
